UNITED STATES PATENT OFFICE.

SAMUEL GEORGE JOWITT, OF YORK, ENGLAND.

WRINGER, MANGLE, OR LIKE MACHINE.

Application filed September 26, 1927, Serial No. 222,065, and in Great Britain September 30, 1926.

This invention relates to wringers, mangles and like machines having power driven rollers, and has for its object to provide improved means whereby when the machine is not in use it can be folded or turned down below the top of the standard or table on which it is mounted, and such standard or table used for other purposes or alternatively another machine such as an ironing machine may be brought into such a position on the standard or table that it can be operated by the power shaft of the wringer or mangle.

The present invention comprises a wringer or like machine of the kind provided with means for turning it down below the level of its supporting standard or table when not in use, and having a driving or power shaft mounted in bearings in the standard or table of the machine wherein such power shaft is coupled to the wringer rotating mechanism by a coupling which is automatically uncoupled when the machine is turned down about a hinge out of using position and recoupled when it is turned up into using position.

The coupling shaft is preferably arranged vertically or at a slight inclination to the vertical, and dowel pins and sockets or other suitable means provided for ensuring the registration of the two parts of the coupling when the machine is turned up into using position. The two engaging members of the coupling may be of any suitable construction such as a driving dog or clutch or constructed as annular members having crown-like spur teeth or serrations, preferably shaped to facilitate entry into one another.

A manner of carrying out the invention is illustrated by the accompanying drawings wherein Figure 1 is a partly sectional elevation of the driving gear end of the machine, Figure 2 an elevation of the main portion of the machine at right angles to Figure 1, and Figure 3 an enlarged view of one member of the coupling.

In these drawings 10 is the wringer or similar machine and 8 the gear box thereof, 11 is a handle of a reversing mechanism. The gear box 8 is extended to form a standard 12 from which extends rearwardly a member 3 constructed to form one member of the hinge about which the wringer can be turned out of using position. The extension 3 is provided with a hinge pin 7 arranged just below the level of a table 13 forming the top of a standard having upright sides 14 and 15.

The other member of the hinge which is connected to the member 3 by the pin 7 is a bracket 4 secured to the underside of the table 13 and provided at its other end with a bearing for a downwardly extending shaft 17 which is the power or driving shaft of the machine.

The hinge member 3 is provided with a vertical stop 18 adapted to engage the vertical standard 14 when the machine is turned down out of use into the position indicated in dotted lines, in Figure 2.

At the top of the table 13 and immediately above the power shaft 17 and concentric therewith is provided a round, square, or suitably shaped slightly tapered socket 5 forming a portion of the hinge bracket 4 and adapted to receive a correspondingly shaped plug 2 extending from the other hinge bracket 3, so that when the machine is turned into using position as shown the plug 2 is firmly fixed in the socket 5.

The socket 16 is extended to form a boss supporting a protecting tube for the shaft 17, and is also provided with a flange 21 for securing it to the upright 14.

In the construction shown, the gearing in the box 8 is driven by a vertical shaft 20 on the lower end of which is formed one of the members 6^a of the coupling, the engaging elements of this member being crown teeth identical with and adapted to be driven by those on the other member 6 of the coupling.

The machine is provided at the other end with any suitable form of hinge coaxial with that at the driving gear end.

What I claim and desire to secure by Letters Patent is:

1. A wringer or like machine of the kind in which the rollers and their driving gear can be turned down out of use below the top of a supporting standard, comprising a power shaft extending downwards from the top of the supporting standard and mounted in bearings in the supporting standard, a vertical driving shaft on the roller driving gear, a shaft coupling having intermeshing toothed members, one of the toothed members of the coupling being fixed on the top of the power shaft in the standard while the other is fixed on the lower end of the vertical shaft of the roller driving gear and so that when the rollers are turned up into using position the upper toothed member of the coupling will be brought into engagement with the lower

- toothed member of the coupling on the power shaft, and when the rollers are turned down the members of the coupling will be brought out of engagement with each other.
5. 2. A wringer or like machine of the kind in which the rollers and their driving gear can be turned down out of use below the top of a supporting standard, comprising a power shaft extending downwards from the top of 10 the supporting standard and mounted in bearings in the supporting standard, a vertical driving shaft on the roller driving gear, a shaft coupling having intermeshing toothed members, means for ensuring engagement of 15 the two members of the coupling, one of the toothed members of the coupling being fixed on the top of the power shaft in the standard while the other is fixed on the lower end of the vertical shaft of the roller driving gear 20 and so that when the rollers are turned up into using position the means for ensuring engagement of the two members of the coupling will be brought into operation and the upper toothed member of the coupling will 25 be brought into and engagement with the lower toothed member of the coupling on the power shaft, and when the rollers are turned down the members of the coupling will be brought out of engagement with each other.
- 30 3. A wringer or like machine of the kind in which the rollers and their driving gear can be turned down out of use below the top of a supporting standard, comprising a power shaft extending downwards from the top of 35 the supporting standard and mounted in bearings in the supporting standard, a vertical driving shaft on the roller driving gear, a shaft coupling having intermeshing toothed members, a socket member extending coaxial- 40 ly upwards from an upper bearing of the power shaft in the standard, and a corresponding plug member extending downwards from a lower bearing of the vertical shaft of the roller gear, one of the toothed 45 members of the coupling being fixed on the top of the power shaft in the standard while the other is fixed on the lower end of the vertical shaft of the roller driving gear and so that when the rollers are turned up into 50 using position the plug will enter the socket and the upper toothed member of the coupling will be brought into and engagement with the lower toothed member of the coupling on the power shaft, and when the rollers are turned down the members of the cou- 55

pling will be brought out of engagement with each other.

4. A wringer or like machine of the kind in which the rollers and their driving gear can be turned down out of use below the top of a supporting standard, comprising a power shaft extending downwards from the top of the supporting standard and mounted in bearings in the supporting standard, a vertical driving shaft on the roller driving gear, a shaft coupling having intermeshing crown toothed members, one of the toothed members of the coupling being fixed on the top of the power shaft in the standard while the other is fixed on the lower end of the vertical shaft of the roller driving gear and so that when the rollers are turned into using position the crown teeth of the upper member of the coupling will be brought in mesh with those of the lower toothed member of the coupling on the power shaft, and when the rollers are turned down the members of the coupling will be brought out of engagement with each other. 70
5. A wringer or like machine of the kind in which the rollers and their driving gear can be turned down about a horizontal hinge out of use below the top of a supporting standard, comprising a power shaft extending downwards from the top of the supporting standard and mounted in bearings in the supporting standard having a rearwardly extending bracket formed as a hinge member, a vertical driving shaft on the roller driving gear running in bearings having a rearward extension formed as a hinge member, a shaft coupling having intermeshing toothed members, one of the toothed members of the coupling being fixed on the top of the power shaft in the standard while the other is fixed on the lower end of the vertical shaft of the roller driving gear and so that when the rollers are turned up into using position the upper toothed member of the coupling will be brought into an engagement with the lower toothed member of the coupling on the power shaft, and when the rollers are turned down the members of the coupling will be brought out of engagement with each other, the rearwardly extending hinge members being connected together to form the hinge about which the rollers can be turned into and out of using position. 80
